(57) CLAIM

I claim the ornamental design for an oval basket hanger, as shown and described.

DESCRIPTION

FIG. 1 is a perspective view of an oval basket hanger;

FIG. 2 is a front view thereof;

FIG. 3 is a side view thereof;

FIG. 4 is a top view thereof; and,

FIG. 5 is a bottom view thereof.

The broken lines depict environmental subject matter only and form no part of the claimed design.
